PHINEHAS HOWARD, OF SAN FRANCISCO, CALIFORNIA, ASSIGNOR TO J. S. JOSSELYN,
WILLIAM B. LAKE, AND B. F. JOSSELYN, OF SAME PLACE.

Letters Patent No. 96,918, dated November 16, 1869; antedated November 3, 1869.

IMPROVED WOODEN PAVEMENT.

The Schedule referred to in these Letters Patent and making part of the same.

To all whom it may concern:

Be it known that I, PHINEHAS HOWARD, of San Francisco, in the county of San Francisco, and State of California, have invented certain new and useful Improvements in Wood Pavements; and I do hereby declare that the following is a full and exact description of the same; reference being had to the accompanying drawings, and to the letters of reference marked thereon.

The nature of my invention is to provide blocks of wood of such shape or outline, that when laid and keyed together, they will be self-supporting, without the employment of nails to hold the blocks to the foundation or bed, each block being a wedge in itself, to bind the whole pavement firmly together.

My invention also relates to fossilizing the wood before the blocks are laid, so that it will be impervious to moisture and dampness, and no shrinking or swelling of the blocks is had; but this process I do not lay any especial claim to, as several patents for preserving wood have already been granted; yet, for fully accomplishing my object, the fossilizing of the wood before use is quite necessary.

Referring to the drawings for a better illustration of my device,

Figure 1 is a longitudinal section.

Figure 2, an elevation of block.

Figure 3, a plan of pavement.

A represents a block of wood, used by me, one side of which is bevelled, while the opposite side is a vertical plane from top to base. These blocks are set on end, one after the other, so as to break joints, and form nearly a V-shaped opening from curb to curb.

For a foundation for my pavement, I employ two-inch planks, which should also be fossilized before being laid.

The street upon which the foundation is laid should be rolled or battered down, to make the earth as compact as possible, and present a smooth and even surface.

It is not intended, in laying down my pavement, to form any considerable crown to the street for it to rest upon, as all wood pavements are, when the surface is wet, more or less slippery, and the animals, in passing over it, are liable to fall, and especially is the danger of falling augmented where the street is more crowning; consequently I prefer to construct my pavement with a flat surface, to prevent these accidents.

When the blocks are laid from curb to curb, as above described, a semi-V-shaped opening is formed, with one side of the angle perpendicular and the other side inclined.

In this opening, I place a strip of wood, C, made wedge-shape, to correspond with the opening, and drive it firmly down, so that the edge of the key or wedge will rest in the vertex.

The wedges should not be made so wide as to extend to the top of the pavement, but a space is left above the wedge, three inches in depth, more or less, in which may be placed clay or gravel, or the natural accumulation of the debris of the street be allowed to fall in, and become packed down, to fill the space, and afford a soft foothold for animals passing over it.

By this arrangement and construction, I provide a wood pavement, at once cheap, simple, and durable, without the use of nails or other adhesive materials to bind and hold it together.

The shape of the blocks themselves, when laid, serve to firmly hold the whole structure together on the line of travel, while the curbing at the sides of the street prevents a lateral movement of the blocks. It can be easily taken up and replaced again, for repairing the street, by common or inexperienced laborers.

Having thus described my invention, I am well aware that shape in itself in a device is not patentable, except, as in this case, where it enters largely into the invention, to make it effectual for the purpose designed; and, after repeated experiments, I am fully convinced that my pavement will stand and be effectual without the wedge above described, and I believe that no other-shaped block can be effectually laid and kept in position without having first been nailed to some foundation; consequently,

I claim as my invention, and desire to secure by Letters Patent—

In a wooden pavement, constructed with semi-V-shaped openings, the employment of the key C, in the manner and for the purpose described.

In witness whereof, I have hereunto set my hand and seal.

P. HOWARD. [L. S.]
